UNITED STATES PATENT OFFICE

139,557

DESIGN FOR A PORTABLE MARKET STAND

William H. Saabye, Kenmore, N. Y.

Application September 9, 1944, Serial No. 115,235

Term of patent 14 years

(Cl. D14—3)

To all whom it may concern:

Be it known that I, William H. Saabye, a citizen of the United States, residing at Kenmore, in the county of Erie and State of New York, have invented a new, original, and ornamental Design for Portable Market Stand, of which the following is a specification, reference being had to the accompanying drawings, forming part thereof.

In the drawings:

Fig. 1 is a front elevational view of a portable market stand showing my new design.

Fig. 2 is a rear elevational view thereof.

Fig. 3 is an end elevational view thereof.

The end of the portable market stand opposite that shown in Fig. 3 is substantially identical to the end shown in Fig. 3.

I claim:

The ornamental design for portable market stand, as shown and described.

WILLIAM H. SAABYE.
